UNITED STATES PATENT OFFICE.

CARL A. LINDSTEN, OF CHICAGO, ILLINOIS, ASSIGNOR OF ONE-HALF TO MARTIN DAHLIN, OF CHICAGO, ILLINOIS.

DESIGN FOR A HEEL-PLATE.

49,747.

Specification for Design.

Patented Oct. 10, 1916.

Application filed January 18, 1916. Serial No. 72,856. Term of patent 3½ years.

To all whom it may concern:

Be it known that I, CARL A. LINDSTEN, a citizen of the United States, residing at Chicago, in the county of Cook and State of Illinois, have invented a new, original, and ornamental Design for Heel-Plates, of which the following is a specification, reference being had to the accompanying drawing, in which—

Figure 1 is a perspective view of a heel plate, illustrating my new design, and Fig. 2 is a perspective view showing the opposite side of the design.

I claim:

The ornamental design for a heel plate as shown.

CARL A. LINDSTEN.
